UNITED STATES PATENT OFFICE.

RAY KELLY, OF KNOBNOSTER, MISSOURI.

ROTARY ENGINE.

1,093,861.

Specification of Letters Patent. Patented Apr. 21, 1914.

Application filed April 18, 1913. Serial No. 762,005.

To all whom it may concern:

Be it known that I, RAY KELLY, citizen of the United States, residing at Knobnoster, in the county of Johnson and State 5 of Missouri, have invented certain new and useful Improvements in Rotary Engines; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to rotary engines, and more particularly to a device of that type wherein a constant volume of fluid is delivered to a rotary member in order to drive said member and mechanism which 20 may be connected therewith.

25 It is the object of the present invention to provide a device of this type wherein fluid medium is delivered against opposite faces of the rotary member and in a manner to exert a pressure on opposite faces of said member, which will tend to revolve same but will press equally against the opposite faces, in order to obviate transverse thrust thereon.

30 It is also an object of the invention to provide the engine with a rotary member having a weighted rim for carrying momentum and thereby induce steady travel of the member.

35 More particularly my engine consists of a rotary member having blades on its opposite faces and extending in spiraled paths from the center of each face, together with a casing, the inclosing sides of which are 40 provided with spiral blades that radiate from the centers similarly, but in opposite directions, to the blades on the adjacent faces of the rotary member, so that when the fluid medium is admitted between the 45 faces of the wheel and casing sides pressure against the blades of the rotary member will tend to revolve said member and thereby produce the desired motive power.

50 In accomplishing the above noted objects I have provided improved details of structure, the preferred form of which is illus-

trated in the accompanying drawings, wherein:

Figure I is a side elevation of a rotary engine constructed according to my invention. Fig. II is a rear view of same. Fig. III is a transverse vertical section on the line III—III, Fig. I. Fig. IV is a side elevation of the rotary member. Fig. V is a side elevation of one of the inclosing sides 60 of the casing.

Referring more in detail to the parts:— 1 designates a base or foundation upon which the engine is mounted and 2 a case which is mounted on the base 1 and adapted 65 for inclosing the working parts of the engine. The case 2 comprises separate side members 3, preferably of cast metal, and having bases 4 which are spaced apart to form a solid foundation for supporting a 70 rotary member and its shafting.

Above its bases 4 each side member comprises a circular concave 5, the central or hub part of which is extended laterally between the vertical plane of the base 4 and 75 provided with a journaled bearing 6 and a downwardly directed port 7, the concaves on opposite members being in circumferential alinement so that their base portions are in close proximity and the bearings 6 in 80 transverse alinement.

Journaled in the bearing 6, in opposite sides of the engine casing, is a shaft 8, the ends of which project beyond the casing in order to connect with power transmitting mechanism (not shown), and fixed on said shaft within the casing is a rotary member 9. The member 9 comprises a hub part, preferably elongated in order to secure a firm bearing on the shaft and to 90 carry out the configuration of the fluid passage presently described.

The rotary member of wheel 9 is of substantial width at its rim 10, and opposite faces of the wheel are concaved to form the 95 annular chambers 11 into which the concave parts 5 of the casing sides project, the arrangement being such, however, that passages or channels 12 are left between the surfaces of the concavo-convex rotary member and casing.

On the rotary member 9 are blades 13

which extend in spiraled paths from the ends of the hub parts of the rotary member to the edge of the periphery thereof through the channels 12, and on the convex faces of the casing sides are blades 14 which extend in spiraled paths throughout the convex surfaces of said sides but oppositely to the rotary blades 13, so that the stationary and movable blades cross and provide rapidly 10 widening expansion chambers for a fluid medium when the engine is in operation, it being apparent that as the blades cross each other the expansion chambers increase in area very rapidly from the center outwardly.

Fixed to the peripheral edges of the concave portions 5 of the casing sides is a rim hood 16 which is spaced from the sides to form a peripheral exhaust chamber 17 which 20 is of greatest area at the bottom of the engine where it communicates with a relief conduit 18.

19 designates feed pipes which lead from any source of supply, such as a boiler, to the 25 intake port 7 of the engine casing, the pipes being of the same diameter so that equal amounts of steam will be delivered to opposite sides of the casing in order to balance the rotary engine and thereby avoid trans- 30 verse thrust which might tend to jam the parts and would, in any event, produce friction sufficient to interfere to some extent with proper operation.

In using the engine, presuming the parts 35 to be constructed and assembled as described, steam entering the casing through conduits 19 is delivered into the annular chambers 11 over the curved surfaces of the rotary member and casing concaves and immedi- 40 ately between the inner ends of the spiraled blades 13—14. As the steam enters the passage its expansion exerts pressure on the blades which tends to move the blades on the revolute member, thereby carrying said 45 member around on its axis. As there is a constant inflow of steam the revolving inner member constantly presents new cham- 50 bers for the expansion of the steam, and as all of the chambers are of the same construc- 55 tion and size, the action of the steam expansion is the same on all of the blades, thereby effecting a steady and even driving action on the rotary member. As the steam ex- 60 pands and loses its driving force it escapes through the enlarged exit port into the ex- 65 haust chamber 17, from which it escapes through the outlet conduits 18, so that there is no tendency of steam to accumulate in the exhaust chamber and thereby interfere 70 with the forward portion of the rotary mem- ber.

Having thus described my invention, what I claim as new therein, and desire to secure by Letters-Patent, is:—

65 1. A rotary engine comprising a station-

ary casing, a rotary member inclosed within the casing and spaced therefrom to provide passages along its opposite faces, oppositely directed spiraled plates on said casing, a rotary member, and means for delivering fluid under pressure into the interior of the casing from opposite sides thereof.

2. A rotary engine comprising a stationary casing, a rotary member inclosed within the casing and spaced therefrom to provide 70 passages along its opposite faces, oppositely directed, spiraled plates on said casing, a rotary member diverging from the hubs of said parts, and means for simultaneously delivering fluid under pressure in- 75 wardly to the passages at opposite sides of the rotary member.

3. A rotary engine comprising a stationary casing, a rotary member inclosed within the casing and spaced therefrom to provide 80 passages along its opposite faces, oppositely directed, spiraled plates on said casing, a rotary member, and separate means for simultaneously delivering fluid inwardly under pressure in balanced quantities to the 85 passages at opposite sides of said rotary member.

4. In a rotary engine, a casing, a rotary member revolvably mounted within the casing and spaced peripherally therefrom to provide an exhaust chamber, an exhaust conduit leading from said chamber, oppositely arranged spiraled blades on adjacent 90 faces of the casing, a rotary member, and means for delivering fluid under pressure in 100 balanced quantities between opposite sides of the rotary member and opposite sides of the casing.

5. In a rotary engine, a casing having an- 105 nular convex portions on its opposite faces, a rotary member contained within the casing and having annular concaves in its op- 110 posite faces into which the convex portions of the casing are projected, and oppositely directed blades on the relatively convex and concave faces of the casing and rotary mem- ber.

6. In a rotary engine, a rotary member having an enlarged rim and concaves be- 115 tween its rim and hub, means for confining a fluid pressure medium within said con- 120 caves, and blades on the rotary member and confining means, for the purpose set forth.

7. In a rotary engine, a casing having an- 125 nular convex portions on its opposite faces and having registering journal bear- 130 ings at the contracted inner ends of said convex portions, a shaft journaled in said bear- ings and extending through the casing, a rotary member fixed on said shaft and hav- 135 ing concaved sides confined between the convex portions on opposite sides of the casing, and having an enlarged rim adapted for ro- 140 tation about the convex portions of the cas- 145 ing, oppositely directed spiraled blades on 150

the rotary member and on the convex portion of the casing, a peripheral hood on the casing forming an annular chamber, and means for delivering balanced volumes of fluid medium to the casing at the contracted centers of the convexed portions, substantially as set forth.

In testimony whereof I affix my signature in presence of two witnesses.

DR. RAY KELLY.
